ICE REFRIGERATOR WITH AN AIR
PUMP CIRCUIT

John M. Hall, New York, N. Y.

Application November 14, 1945, Serial No. 628,571

9 Claims. (Cl. 62—72)

1

This invention relates to new and useful improvements in a refrigerator or ice box.

More specifically, the present invention proposes the construction of a refrigerator characterized by having a cabinet with shelves and an ice shelf at the top, and thereabove a fan compartment for drawing air in at the top and forcing it downward over the ice and through the box where it may leave at the bottom through an opening.

A further object is to provide a refrigerator as aforesaid in which the top and bottom inlet and outlet openings are controlled by movable draft regulators.

Another object is to provide a refrigerator of the aforesaid type in which vents are also provided in the front door adjacent the ice shelf.

A further object is to provide a refrigerator of the aforesaid type having means for circulating the air in a partially continuous cycle within the cabinet.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a refrigerator constructed in accordance with this invention, the door being open and a cake of ice being supported on the ice shelf.

Fig. 2 is a section on the line 2—2 of Fig. 1.

Fig. 3 is a front view of a refrigerator constructed in accordance with a modification of this invention.

Fig. 4 is a view, similar to Fig. 2, of a refrigerator constructed in accordance with a further modification of this invention.

The refrigerator or icebox, according to this invention, comprises a cabinet 10 standing on four legs 11. The cabinet has a top wall 12, a perforated bottom wall 13, side walls 14, a rear wall 15 and a front door 16. The door has hinges 17 and a latch 18.

The top wall of the refrigerator has an opening 19 over which is secured a casing 20 having a top wall 21, side walls 22, a rear wall 23 and a front wall 24. An electric fan 25 depends from the top wall 21 centrally of the opening 19. Adjustable shutters 26 are disposed in holes 27 in the walls 22. Mounted in the front wall 24 is an electric regulator 28 for controlling the motor speed by variable resistor. The side walls 14 of

2

the cabinet have openings 29 at their bottom covered by hinged flaps 30 having end walls 31 which are slidably disposed in slots 32 in the side walls. A plunger 30^a is provided for closing or opening 5 the flap 30. The lower end of plunger 30^a is formed with rack teeth 30^b meshing with pinion 30^c. This pinion also meshes with a sector gear 30^d fixed on the axle 30^e of the hinged flap 30.

The electric fan pulls air in through the shutter 26 and the air leaves the cabinet through the holes 29. The flow of air can be controlled by 10 means of the shutters 26 and flaps 30. Also the fan will be a conventional variable speed fan so that its pumping action may be adjusted.

15 Inside the cabinet is a rack including side walls 33 parallel to and spaced from walls 14. Three shelves 34 are supported by the side walls. The top shelf has a border 35 and is adapted to support a cake of ice 36. A pipe 37 extends from 20 the ice shelf through the other shelves and through the bottom of the ice box for draining off the water formed by the melting of the ice.

The operation of the ice box is as follows:

The fan is turned on after a cake of ice has 25 been inserted in the box and it draws in air through the shutters 26, forces it downwardly over the cake of ice and downwardly through the passages formed by the spaces between the walls 14 and 33 to the openings 29. The flow can 30 be regulated by means of the shutters 26, the flaps 30 and the speed of the fan. If desired, at times, the fan may be turned off. Also the shutters and flaps may be closed, or any desired arrangement of the shutters, flaps and fan may 35 be effected to obtain the desired condition.

The fan, by drawing in fresh air, keeps the ice box well ventilated and thus keeps the food 40 fresh and untainted by ice box odors. Also the flow of cool air from the ice box into the room containing it, which is usually the kitchen, helps to keep the kitchen cool and comfortable. In winter, when it is cold, the openings may be closed to prevent air from escaping from the ice box. In summer, when a great deal of air passes 45 through the box, the openings may be opened. When the shutters and flaps are both closed, the perforations in the bottom wall 13 permit a uniform escape of a limited amount of air. The amount of flap opening may be controlled by 50 moving the plunger 30^a. The opening 29 may be completely shut by moving the plunger 30^a upwardly until the flap 30 closes the opening 29.

The refrigerator of Fig. 3 is identical with the refrigerator of Fig. 1, except that it has a hole 55 38 in the door 16. Shutters 39 in the hole 38

are controlled by a knob 40. Other parts of this refrigerator corresponding to like parts of the refrigerator of Fig. 1 are indicated by like references with an accent added.

The refrigerator shown in Fig. 4 includes a modified form of the invention. Upon the legs or feet 11" the bottom wall 13" is supported, and from this bottom wall the inner vertical wall 33" rises. The wall 13" is extended outwardly of the vertical inner wall 33", but the air discharge openings 13^a of this bottom wall are confined to the area bounded by the vertical wall 33". An outer wall 41 rises vertically from the bottom wall 13" and is provided on its upper end with a horizontal wall 44, from which rises the vertical wall 45, having openings in which the shutters 47 are disposed. The vertical wall 45 is provided with a top horizontal wall 48, on which the fan 25" is supported.

An intermediate vertical wall 14" is disposed between the inner vertical wall 33" and the outer vertical wall 41, in spaced relation to both of said walls 33" and 41, to provide the inner vertical passage 15" between the inner wall 33" and said intermediate wall 14" and an outer vertical passage 15" between said outer vertical wall 41 and the intermediate vertical wall 14".

Air is drawn through the shutter controlled openings in the vertical wall 45 to the central air well 25^a of the fan chamber, and flows downwardly over the ice through the passage 19, through the inner vertical passage 15", and thence through the lateral passages 14^a of the intermediate wall 14", to the outer vertical passage 15^a, to the outer and upper passage 22^a, between the inner vertical wall 22" and the outer vertical top wall 45, and out through the shutter controlled openings, in part, and in part back over the ice. A drainage pipe 37" is provided for ice water.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves.

2. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages

for the flow of air to said side wall holes, said rack further having a top ice shelf and therebelow food shelves and a pipe extending from said ice shelf through said other shelves and said cabinet bottom wall.

5. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves and perforations in said cabinet bottom wall for permitting escape of air.

20 6. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves and means for adjusting said flap for controlling the flow of air, said means including a vertical, slidable plunger, rack teeth at the bottom of said plunger meshing with a pinion, said pinion being also in mesh with a section gear connected to the axle of the said flap.

25 7. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves, said shutters and flap being 30 adjustable and said fan having different speeds for controlling the flow of air.

8. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves.

35 9. An ice box comprising a cabinet having a top wall, a bottom wall, side walls, a rear wall and a front door, said top wall having a hole and said side walls having holes adjacent their bottom, a casing over said top wall hole having side walls

walls, a top wall, a rear wall and a front wall, said casing side walls having holes, a fan in said casing, shutters in said casing side wall holes, a flap over said cabinet side wall holes, and a rack in said cabinet having side walls spaced from said cabinet side walls and forming therewith passages for the flow of air to said side wall holes, said rack further having a top ice shelf and therebelow food shelves, said door having a hole and adjustable shutters in said hole.

8. An ice box comprising a cabinet having a top wall, a bottom wall, side walls, a rear wall and a front door, said top wall having a hole and said side walls having holes adjacent their bottom, a casing over said top wall hole having side walls, a top wall, a rear wall and a front wall, said casing side walls having holes, a fan in said casing, a rack in said cabinet having side walls spaced from said cabinet side walls and forming therewith passages for the flow of air to said side wall holes, said rack further having a top ice shelf and therebelow food shelves, and a wall parallel to each side wall of said cabinet and casing and spaced therefrom forming other passages, said last mentioned walls each having an opening adjacent said casing openings, and adjustable shutters in said last mentioned wall openings whereby said fan will suck air in through said shutters into said casing, force it over said ice to said openings in said cabinet side walls and therefrom back to said casing openings.

9. An ice box comprising a cabinet having a top wall, a bottom wall, side walls, a rear wall and a

front door, said top wall having a hole and said side walls having holes adjacent their bottom, a casing over said top wall hole having side walls, a top wall, a rear wall and a front wall, said casing side walls having holes, a fan in said casing, a rack in said cabinet having side walls spaced from said cabinet side walls and forming therewith passages for the flow of air to said side wall holes, said rack further having a top ice shelf and therebelow food shelves, and a wall parallel to each side wall of said cabinet and casing and spaced therefrom forming other passages, said last mentioned walls each having an opening adjacent said casing openings, and adjustable shutters in said last mentioned wall openings whereby said fan will suck air in through said shutters into said casing, force it over said ice to said openings in said cabinet side walls and therefrom back to said casing openings, said cabinet bottom wall being perforated providing the only air outlet of said ice box.
